ROTARY CIRCUIT BREAKER

André Guillaume, La Plaine Saint-Denis, Seine, France, assignor to Societe Anonyme dite: Forges et Ateliers de Constructions Electriques de Jeumont, Paris, France, a corporation of France

Application June 1, 1951, Serial No. 229,359
In France June 9, 1950

5 Claims. (Cl. 200—150)

1

The present invention relates to improvements in rotary circuit breakers of high breaking power, the rotary contacts of which operate in a small volume of oil; see for instance U. S. Pat. No. 2,507,971.

It has previously been proposed to immobilize the arcs of such circuit breakers by means of circular arc-guiding channels in which the rotary contacts move, the arcs being maintained in the interior of these channels by the flow of quenching fluids exhausted from the interrupting chamber.

A primary object of the present invention is to reduce the mechanical forces (pressures) which appear in circuit breakers of this type and, by such reduction, to improve the performance of the circuit breaker and to increase its so-called breaking power.

A further object of the invention is to improve the fixation of arcs and the blow-out effect of the quenching fluids.

The foregoing objects are realized by the present invention which involves a special construction and arrangement of rotary contacts and of arc-guiding channels, the latter being directly associated with damping means disposed in their immediate vicinity.

According to the invention, the arc fixation channels have the form of relatively deep annular grooves of substantially trapezoidal cross-section, the axis of symmetry of the said cross-section being parallel to the axis of rotation of the circuit breaker. Moreover, the said guiding channels are interconnected with chambers, in the form of recesses or bores or the like, which are partially filled with oil and are positioned in the immediate vicinity of said channels in order to damp and lengthen the time of effectiveness of, the hydraulic flow effects which appear in the said channels.

Additional features and objects of the present invention will be evident from the following description, with reference to the accompanying sheet of drawings, of a presently-preferred exemplary embodiment of the invention.

On the said sheet of drawing, Fig. 1 is a somewhat diagrammatic section through a two-arc interrupting chamber, Fig. 2 is a horizontal cross-section taken along line I—I of Fig. 1, and Fig. 3 is a similar cross-section taken along line II—II 50

of Fig. 1.

The aforesaid chamber is a cylindrical housing formed by a stationary cylinder 7 of insulating material and two spaced end plates 16 and 18 of insulating material fixed in the interior thereof, 55

2

as shown. Rotary shaft 1, also of insulating material, is mounted to rotate within the said cylinder 7 and plates 16 and 18. The shaft 1 passes without appreciable play through the circular openings provided in plates or partitions 16 and 18, which are reinforced by additional end partitions 15 and 17. Shaft 1 carries two spaced electrically conductive contact arms 2, which co-operate, respectively, with fixed contacts 3 and 4. 10 Rotary contacts 2 are electrically interconnected by a suitable conductive connector member 2a arranged as shown interiorly of shaft 1 which, to this end, may be tubular. Each contact arm 2 is bent in the manner illustrated on the drawing so that the terminal end thereof extends in a direction parallel to shaft 1.

The end of the upper contact 2 moves within downwardly-opening annular channel 9, provided for the guidance of the upper arc and being formed in the upper insulating plate 16. Channel 9 is relatively deep and takes the form of a downwardly-opening annular groove having a trapezoidal cross-section with smooth angles, which facilitates the flow of oil and enables the realization of a very effective fixation in space as well as an efficient quenching of the upper arc which is formed between upper contact 2 and fixed contact 3 which, as shown, is located in the channel 9.

20 The downwardly extending end of the lower rotary contact member 2 moves within a similar upwardly-opening channel 9a, provided in the plate 18 for the guidance of the lower arc which is formed between said contact 2 and a fixed contact 4, located as shown, in channel 9a enclosing the path of the said lower contact 2. The described relationship of parts effects an efficient immobilization and quenching of the said lower arc.

25 The downwardly extending end of the lower rotary contact member 2 moves within a similar upwardly-opening channel 9a, provided in the plate 18 for the guidance of the lower arc which is formed between said contact 2 and a fixed contact 4, located as shown, in channel 9a enclosing the path of the said lower contact 2. The described relationship of parts effects an efficient immobilization and quenching of the said lower arc.

30 Channel 9 comprises a plurality of blow-out and exhaust openings 10 extending upwardly from the bottom of the annular groove thereof through to the upper surface of plate 16. Outlet openings 10 are spaced in circular arrangement around shaft 1 in alignment with upwardly outwardly-flared passages 13 extending through the outer plate 15 of insulating material, mounted on plate 16. It will be understood that the passages 13, which correspond in number to the openings 10, are, like the latter, disposed in circular arrangement in plate 15 around shaft 1. The passages 10, 13 have preferably the form of conventional blow-out nozzles, the effect of which, in combination with the cross-sectional form of channel 9, is to facilitate the exhaust

flow and to produce a very efficient deionization of the upper arc.

A number of downwardly-opening chambers 19, which may for instance be in the form of bores, are provided in plate 16. These chambers are disposed in circular arrangement around shaft 1, as shown in Fig. 2. A similar series of downwardly-opening recesses or bores 19a is provided in plate 15, while a similar series of recesses or bores 20 and 20a is also provided in each of annuli 18 and 18a, respectively, according to Fig. 3. These recesses or bores 19, 19a, 20 and 20a are partly filled with oil, the upper portion of each bore being filled with gas produced by previous interruptions, so that all recesses operate as yielding elements after the manner of dash-pots or shock absorbers. In order more efficiently to damp and prolong (i. e. extend over an increased period of time) the pressure effects which arise in the interior of channels 9 and 9a and to better immobilize the arcs in these channels, the recesses or bores 19, 19a, 20 and 20a are positioned in close proximity to, i. e. in the immediate vicinity of, the said channels and are connected to the latter, as shown. Bores 19a are connected to channel 9 by way of short conduits 21, while bores 20 and 20a are connected to channel 9a by way of short conduits 22 and 22a, respectively. This arrangement makes it possible for the gases produced by the arcs to collect in the upper portions of the said bores and, by the compression of such trapped gas, to produce currents of oil which improve the fixation or localization of the arcs in both channels 9 and 9a.

In consequence of the described relationship of parts, the upper arc is maintained in its blow-out position in the interior of channel 9, not only by the fluids which are exhausted through orifices 13 but also by the fluids which move through conduits 21 to bores 19a. The lower arc is maintained at the bottom of channel 9a by the fluids which pass through conduits 22 and 22a to recesses 20 and 20a.

It is known that the gases which are formed suddenly by arcs of interruption give rise to overpressures of two kinds. The one type of overpressure, relatively moderate, has a relatively long duration of the order of a fraction of a second; the other type of overpressure is of the impulse type, the waves of which have a very steep front of short duration but with very high peak values which may exceed the limits of strength of the apparatus.

When the gas-filled cavities are remote from the arcs, as in known apparatus these overpressure impulses are propagated and are reflected throughout the apparatus, subjecting the latter to very high stresses. On the other hand, when the said cavities are positioned, in accordance with the present invention, practically at the very point where the said steep front waves of pressure are created, these waves are absorbed on the spot and only the moderate overpressures, relatively slow in their formation and action, pro-

duce the proper acceleration of the oil to assure energetic and prolonged blowing of the arc.

These moderate overpressures produce a prolonged flow of deionizing fluids through the upper channel 9 and blow-out passages 10, 13, the nozzle type of which facilitates the flow-out and appreciably improves the blow-out.

As a result, the present device is capable of breaking more powerful arcs without producing excessive pressures, i. e. the apparatus has an increased breaking power.

It will be understood that the chamber defined between plates 16 and 17 and cylinder 7 is filled with oil or other suitable quenching fluid up to level 8; also that the contacts 3 and 4 are severally connected with lead wires 5 and 6.

Having thus disclosed the invention, what is claimed is:

1. In a rotative high-power circuit breaker of the low oil-volume type comprising an interrupting unit including an insulating housing having spaced upper and lower end walls defining upper and lower circular arc-guiding channels with outlet openings from the upper channel, and also comprising a fixed contact in each of said channels and a rotatable contact engageable with each of said fixed contacts, at least one circularly-arranged series of downwardly opened gas-filled damping chambers in each of said upper and lower walls, said circular series being arranged in the immediate vicinity of the corresponding circular channel, and each said channel having a trapezoidal cross-section with smooth angles, the axis of symmetry of this cross-section being parallel to the axis of rotation of said circuit breaker.

2. A relationship of parts according to claim 1, wherein each of said end walls comprises a plurality of circularly-arranged series of said damping chambers which have the form of vertical bores which retain a part of the gases produced by the arcs.

3. A relationship of parts according to claim 1, wherein the active end portions of said rotatable contacts extend inside of said circular channels parallel to said axis of rotation.

4. A relationship of parts according to claim 1, wherein said outlet openings have the form of hydraulic blow-out nozzles interconnecting said upper channel with the outside.

5. A relationship of parts according to claim 1, and short interconnections between said circular channels and the lower parts of the associated damping chambers, said interconnections being located in the immediate vicinity of the arcs.

ANDRÉ GUILLAUME.
